UNITED STATES PATENT OFFICE.

GEORGE W. GOMBER, OF CONYNGHAM, PENNSYLVANIA, ASSIGNOR TO A. W. DRAKE MANUFACTURING CO., OF HAZLETON, PENNSYLVANIA, A CORPORATION OF PENNSYLVANIA.

CORK-EXTRACTOR.

1,375,382.

Specification of Letters Patent. Patented Apr. 19, 1921.

Application filed June 8, 1920. Serial No. 387,380.

To all whom it may concern:

Be it known that I, GEORGE W. GOMBER, a citizen of the United States, residing at Conyngham, in the county of Luzerne and State of Pennsylvania, have invented a new and useful Cork-Extractor, of which the following is a specification.

This invention relates to cork extractors. The object of the invention is to provide a combination cork screw and cork pulling device whereby corks projecting a sufficient distance without the bottle can be readily pulled without using the cork screw, while corks leaving but little or no hold may be pulled in the usual way with the cork screw.

A further object of the invention is to provide a novel form of cork screw which will not break up the cork as does the ordinary form of coil cork screw and which will secure a stronger pulling hold on the cork and will enter the cork more easily.

The device of the present invention will be found to be very efficient in pulling corks which can not be removed in the usual way by prying or without breaking into small pieces.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing:—

40 Figure 1 is a perspective view of the preferred embodiment of the invention.

Fig. 2 is a detail partly in cross-section of one of the jaws illustrating the manner of attaching the cork screw to said jaw.

45 Fig. 3 is a cross-section illustrating the manner in which the rolled section for holding the cork screw on the jaw is formed.

Fig. 4 is a longitudinal cross section of that portion of the cork screw projecting 50 beyond the jaw.

The device of the invention comprises substantially a pair of pivoted levers each having a jaw to one of which a novel form of cork screw is secured. The handles or levers are designated by the numeral 5 and

the jaws by the numerals 6 and 7. One of the jaws 7 is bent to provide a concave gripping face 8 having serrations or teeth running transversely thereof. The other jaw 6 has a gripping face 9 which is substantially plane and is provided with serrations or teeth similar to the opposed gripping surface. The two jaws are of equal length so that when they are closed their outer edges meet. The jaw 6, which has the plane gripping face 9, is provided with a roll 10. This roll receives the end of a cork screw 12 of peculiar form. The cork screw 12 may be held within the roll by an ordinary screw head and by its threads 14, or it may be soldered therein. In the illustrated embodiment of the invention, the cork screw 12 is held within the roll by providing a depression or groove 13 in the shank thereof and by pressing down the roll, as at 11, 75 to fit into the groove 13 whereby longitudinal movement in either direction of the screw with respect to the roll is prevented. The roll 10 terminates with the outer edge or end of the gripping surface 9, while the 80 threaded portion of the screw projects outwardly from the jaw 6 so as to form a substantial continuation thereof.

The cork screw 12 is formed something like a wood screw but is more tapering, is 85 of greater pitch, and is more deeply milled than the ordinary wood screw. The screw might be described as comprising a solid shank of tapering diameter having a thread of a depth which progressively increases as 90 the shank tapers. This statement will be best understood from an inspection of Fig. 4 of the drawing. In other words, the threads are deepest where the shank tapers the most.

95 Tests have shown that deeply milled screws of the form shown in the drawings will secure a stronger pulling hold on the cork than a coil screw, will start to enter the cork more easily, can be kept in the center of the cork, and that with them the corks can be pulled with very little breaking up as compared with the ordinary coil screw.

In case the cork projects a sufficient distance beyond the bottle to allow a good hold 105 to be obtained, the gripping faces 8 and 9 of the jaws may be closed about the cork, whereupon the same may be readily pulled without any possibility of mutilation of the cork.

When the screw portion of the extractor is used, the handles or levers when separated render the turning of the screw into even a tight cork a very easy operation. 5 After the screw has become embedded its full length in the cork, the free jaw 7 may be closed, whereupon if the cork is well into the bottle the jaw will lie over the top of the bottle and provide a convenient fulcrum for 10 starting the cork. The roll 10 and jaw 9 serve as a head for the screw, preventing entrance of the lever into the hole in the cork cut by the screw.

When the pivoted handles are used, they 15 give sufficient leverage for gripping and holding new and tight corks. If desired, after the cork is gripped between the jaws, the two handles on one side and the screw on the other side may be grasped by the fingers and the entire implement pulled upwardly, whereupon the most obstinate cork 20 will give way. From what has been said, it should be clear that the levers have an intimate coöperation with the screw, and the 25 screw with the levers in effecting the single result of extracting corks. The screw cannot be used independently of the handles, nor the levers independently of the screw, without sacrificing most of the advantages 30 of my invention.

In some forms of the invention it may be advisable to employ the ordinary coil screw, and in certain of the claims I have provided for this.

35 What is claimed is:

1. A cork extractor comprising a pair of pivoted levers having jaws, and a screw mounted on one of the jaws and extending outwardly and longitudinally therefrom.

40 2. A cork extractor comprising a pair of pivoted levers having jaws, and a screw mounted on one of the jaws and extending outwardly therefrom to form a substantial continuation thereof, the threads of the 45 screw being presented only beyond the end

of the jaw, the shank of the screw tapering from the jaw end to the free end of the screw.

3. A cork extractor comprising a pair of pivoted levers having jaws, and a screw 50 mounted on one of the jaws and extending outwardly therefrom, said screw comprising a shank of tapering diameter having a thread of a varying depth, said shank having a greater taper in the portion comprehended approximately between its mid point and the free end of the screw and being largest where it is attached to the jaw.

4. A cork extractor comprising a pair of pivoted levers having jaws, one of said jaws 60 having a plane gripping face, the other jaw being bent to provide a concave gripping face, and a screw mounted on that jaw having the plane gripping face and extending outwardly therefrom to form a substantial 65 continuation thereof, the threads of the screw being presented only beyond the end of the jaw, the curved or concave jaw end providing a fulcrum for the implement when engaged over the mouth of the bottle 70 whereby a deeply driven-in cork may be started without pulling the screw out of the cork or otherwise mutilating the cork.

5. A cork extractor comprising a pair of pivoted levers having jaws, one of said 75 jaws having a roll, a headless screw having an unthreaded portion thereof received within the roll, a groove provided in that portion of the shank of the screw which is housed within the roll, said roll being de- 80 pressed so that a portion thereof is forced into the groove to hold the screw against both longitudinal and rotative movement, said screw extending beyond the end of the jaw upon which it is mounted to form a sub- 85 stantial continuation thereof.

In testimony, that I claim the foregoing as my own, I have hereto affixed my signature.

GEORGE W. GOMBER.
